UNITED STATES PATENT OFFICE.

EUZELIA POOLE, OF RICHMOND, VIRGINIA.

ABDOMINAL SUPPORTER.

Application filed February 15, 1921. Serial No. 445,214.

To all whom it may concern:

Be it known that I, EUZELIA POOLE, a citizen of the United States, residing at Richmond, in the county of Henrico and State 5 of Virginia, have invented certain new and useful Improvements in an Abdominal Supporter, of which the following is a specification.

This invention relates to abdominal supporters and the main object thereof is to provide a simple and efficient device of this character which may be used either in maternity cases or by persons having abnormally large or fleshy abdomens.

Another object is to so construct such a supporter that it may be satisfactorily adjusted to fit the figure of the user and when so adjusted will retain its position.

Another object is to so construct such a supporter that it will be longitudinally yieldable at its top or upper portion and substantially unyieldable at its bottom or lower edge except at its front or back so that it will comfortably support the weight of 25 the abdomen.

Another object is to provide simple and comfortable means for holding the supporter against upward riding.

With these and other objects in view, the 30 invention consists in certain novel features of construction as hereinafter shown and described, and specifically pointed out in the claims.

In the accompanying drawing:

Fig. 1 represents a front elevation of 35 this improved supporter shown applied.

Fig. 2 is a rear elevation thereof.

Fig. 3 is a view of the supporter spread out in open position viewed from the outside.

Fig. 4 is a similar view viewed from the inside, parts being broken out, and,

Fig. 5 is an enlarged detail horizontal section taken on the line 5—5 of Fig. 3.

In the embodiment illustrated, the numerals 1 and 2, respectively, designate the left hand front section and the right hand front section of a supporter, on the outer vertical edge portion of each of which sections is inserted a reinforcing strip or stay as 3 and 4, respectively, of well known form which stays are provided with hooks 5 and eyes 6 whereby said vertical edge portions of said sections may be releasably and closely united in a well known manner.

These front sections 1 and 2 are construct-

ed exactly alike and hence one only will be described in detail. Each of said sections is composed of a body portion 7 formed of elastic webbing positioned so as to be longitudinally yieldable and transversely unyieldable, elastic webbing as is well known being yieldable in one direction and non-yieldable in the other. Stitched to the lower edge of this body member 7 is a substantially triangular member 8 composed of non-elastic woven fabric, the lower edge of which is curved inwardly and reinforced by a binding 9. This binding 9 merges at its front end into the casings 3 or 4 as the case 70 may be and at its rear end merges into a similar casing 10 arranged on the inner or rear vertical edge portion of the front section and which is provided with eyelets 11 to provide for its connection with the adjacent rear section presently to be described.

A strip of rubber tubing 12 is fixedly secured at one end to the front lower edge of the front section and carries at its other end a tape or non-elastic strip of webbing 13 80 secured by any suitable means to the rubber strip 12 a clip 14 being here shown for this purpose. This tape or strip 13 has a hook 15 adjustably mounted thereon by a sliding buckle 16 and is designed to detachably engage a cooperating element 17 carried by the adjacent back section as will be presently described.

The front sections 1 and 2 are separately united by lacing strings 18 and 19, respectively, to the adjacent vertical edge portions of two back or rear sections 20 and 21, respectively, which are interposed between said sections 1 and 2, the other vertical edge portions of said rear sections being connected together by a strip of elastic webbing 23 which terminates near their upper ends, the portion above said webbing being connected adjustably by a lacing string 24. It will thus be seen that the two rear sections are 100 yieldably connected longitudinally at their lower edge and throughout the greater portion of the body thereof but are held against longitudinal movement at their upper portion by the lacing string 24 which however 105 may be adjusted to adapt the device to fit figures of different sizes.

These rear sections 20 and 21 are reinforced along their upper edges by a binding strip 25 and similarly reinforced at their 110 lower edges by strips 26 and each has a pocket or housing 27 extending from one

edge to the other midway its ends as is shown clearly in Figs. 3 and 4, said pocket being formed by applying an additional layer of non-yieldable woven fabric 28 on the inner face of the section as is shown clearly in Fig. 4. Bone receiving casings 29 are formed at the opposite side edges of each pocket and receive stiffening members 30, preferably constructed of whale bone 10 although they may be made of any other suitable material. Similar stiffeners 31 are located in casings at the opposite side edges of the webbing strip 23 at the back of the supporter which extend entirely to the top 15 of each section. These stiffeners being the only ones employed throughout the structure of the supporter.

Arranged in each of the housings 27 is an elastic loop 17 constructed of a rubber 20 lacing or other suitable yieldable strip which is attached at its ends with a respective stiffener receiving casing with its intermediate portion extending through two eyelets 32 formed in the outer ply of said pocket 25 27, said eyelets being arranged in transverse alignment or rather longitudinally relatively to the supporter as is shown clearly in Fig. 3.

In the use of this improved supporter the sections having been connected as shown in 30 the drawings and adjusted by means of the lacings to fit the figure of the user the tubular rubber straps 12 are passed around the legs from the rear toward the front and detachably connected with the yieldable loops 35 17 and the cooperating fasteners 5 and 6 engaged as shown in Fig. 1. If any further adjustments are needed after the device has been placed on the body of the user they may be made by means of the lacings connecting the front with the rear sections and when so positioned will comfortably support the weight of the abdomen, the supporter being substantially unyieldable for the major portion of its length circumferentially 40 around its lower edge and yieldable circumferentially at the upper portion thereof to adapt it to conform to the figure of the user, and to yieldably but firmly support the organs.

50 The preferred embodiment of the inven-

tion is disclosed in the drawings and set forth in the specification, but it will be understood that any modifications within the scope of the claimed invention may be made in the construction without departing from the principle of the invention or sacrificing any of its advantages.

What is claimed is:

1. A supporter comprising right and left hand front sections each having on the outer vertical edge a reinforcing strip or stay with said sections releasably united and each formed with a body portion of elastic webbing positioned to be longitudinally yieldable and transversely unyieldable, a triangular member of non-elastic woven fabric stitched thereto with the lower edge curved inwardly and reinforced, said front sections being separately united by lacing at the adjacent vertical edges of the two back or rear sections with portions of the other vertical edges of the rear sections connected by elastic webbing, and the portions above said webbing being adjustably connected together, whereby the two rear sections are yieldably connected together longitudinally at their lower edges and throughout the greater portion of the body thereof but are held against longitudinal movement at their upper edges.

2. A supporter of the class described comprising separably and adjustably connected front and rear sections, the rear sections having their lower portions elastically connected and their upper portions non-elastically but adjustably connected, said rear sections having transversely arranged pockets, the outer wall of each pocket being provided with transversely spaced and aligned eyelets, an elastic loop mounted in each pocket with the ends thereof secured to the walls of the pocket and the looped portion extended through said eyelets on the outer face of said supporter, and elastic straps connected at one end to the front portions of said front sections, and having means at their other ends for detachable engagement with said loops.

In testimony whereof, I affix my signature hereto.

EUZELIA POOLE.
